UNITED STATES PATENT OFFICE.

ADOLPH F. PRAHM, OF INDIANAPOLIS, INDIANA.

LOCOMOTIVE HEAD-LIGHT.

SPECIFICATION forming part of Letters Patent No. 393,173, dated November 20, 1883.

Application filed April 17, 1883. Serial No. 270,926. (No model.)

To all whom it may concern:

Be it known that I, ADOLPH F. PRAHM, a citizen of the United States, residing at Indianapolis, in the county of Marion and State of Indiana, have invented a new and useful Improvement in Locomotive Head-Lights, of which the following is a specification.

My invention relates to an improved means for obstructing or modifying the light from a locomotive head-light.

The object of my improvement is, first, to enable the engineer to draw a curtain partly or wholly across his head-light, either from his station in the cab or at the side of the head-light; second, to so arrange said curtain that it will be protected from injury either by the weather or heat from the lamps.

The accompanying drawings illustrate my invention.

20 Figure 1 is a side elevation. Fig. 2 is an interior view, on a larger scale, of the front of the lantern, showing the curtain drawn partly across the opening. Fig. 3 is a transverse section at *a*, Fig. 2.

25 *A* is a curtain, of flexible material. One end of curtain *A* is mounted on a spring curtain-roll, *B*, which may be of any well-known form.

30 *C* is a cylindrical case, having brackets *d d* at each end, by means of which it may be secured to one of the interior side walls of the lantern, and a narrow longitudinal slot, through which the curtain passes.

35 The spring curtain-roll *B* is centrally mounted, so as to revolve within the case, and the curtain, when rolled thereon by the recoil of the spring, is contained in the annular space between the exterior of the roll and the interior of the case. The free edge of the curtain

40 is secured to a light metallic rod, which is bent at a right angle to form a horizontal arm, *e*, and a vertical arm, *f*. Arm *e* projects out through a hollow stud, *h*, which is secured to the outside of the lantern and terminates in a

45 knob, *i*, and forms a guide-bar which controls the movement of the curtain, and arm *f* projects above the upper edge of the curtain into a grooved guide, *j*, secured to the front of the lantern. Secured to arm *f*, and extending outward along arm *e*, is a cord, *k*, which passes out

through a tube, *l*, which is secured to stud *h*, and forms a curved passage through which the cord may run easily downward and backward to the engineer's cab. (Not shown.)

5 S is a set-screw for the purpose of fixing arm *e* in any desired position.

In operation, the engineer, desiring for any purpose to cover his head-light, as when on a side track, or desiring to use his head-light as a signal by partly covering it, may do so from 60 his station in the cab by simply drawing the curtain the required distance across the glazed opening of the head-light by means of the cord *k*, the cord being made fast to hold the curtain extended; or the curtain may be drawn at the 65 front of the engine by seizing knob *i* and drawing arm *e* outward and securing it in position by the set-screw *S*. When the cord *k* is released, the curtain is rerolled on the spring-roll by the recoil of the spring, in the usual 70 well-known manner.

I am aware that a curtain has before been used to cover a head-light on the outside, the curtain-roll being placed above the opening and adapted to be operated from the front of 75 the engine only, and I do not claim such a device; but

I do claim as my invention—

1. In a head-light, the combination of the lantern having a glazed opening, the curtain 80 mounted on a spring-roller, the cylindrical case inclosing said curtain and spring-roller and secured to one side of the glazed opening within the lantern, the guide-bar secured to the free edge of the curtain and projecting through the 85 side of the lantern, and the cord attached to the curtain and extending along said guide-bar and out through suitable guides, all arranged to co-operate substantially as and for the purpose specified. 90

2. In a head-light, the combination, with the lantern having a glazed opening, of a curtain mounted on a spring-roller within the lantern on one side of the opening, a guide-bar attached to the free edge of the curtain and projecting through a hollow stud in the side of the lantern, and means, substantially as shown and described, for adjustably securing the guide-bar in position, all substantially as and for the purpose specified. 95

3. In a head-light, the lantern having a glazed opening, the spring curtain-roller, the curtain mounted thereon, the cylindrical case surrounding the roller and the curtain, the rod bent to form arms *e* and *f* and secured to the free edge of the curtain, and the cord also secured to the free edge of the curtain and ex-
- tending along arm *e*, all combined and arranged to co-operate substantially as specified.

ADOLPH F. PRAHM.
